(57) **CLAIM**

The ornamental design for a fluid dispenser, substantially as shown.

DESCRIPTION

FIG. 1 is a perspective view of a fluid dispenser, according to an embodiment;

FIG. 2 is a front view of the fluid dispenser, according to the embodiment;

FIG. 3 is a rear view of the fluid dispenser, according to the embodiment;

FIG. 4 is a right side view of the fluid dispenser, according to the embodiment;

FIG. 5 is a left side view of the fluid dispenser, according to the embodiment;

FIG. 6 is a top view of the fluid dispenser, according to the embodiment; and,

FIG. 7 is a bottom view of the fluid dispenser, according to the embodiment.

The broken lines in the figures show portions of the fluid dispenser that form no part of the claimed design.

1 Claim, 3 Drawing Sheets
